UNITED STATES PATENT OFFICE.

CHARLES H. PATTEN, OF PROVIDENCE, RHODE ISLAND, ASSIGNEE TO CHARLES E. HANCOCK COMPANY, OF PROVIDENCE, RHODE ISLAND, A CORPORATION OF RHODE ISLAND.

CIGAR-CUTTER.

1,058,999.

Specification of Letters Patent. Patented Apr. 15, 1913.

Application filed October 31, 1912. Serial No. 728,892.

To all whom it may concern:

Be it known that I, CHARLES H. PATTEN, a citizen of the United States, and resident of the city of Providence, in the county of Providence and State of Rhode Island, have invented certain new and useful Improvements in Cigar-Cutters, of which the following is a specification.

This invention relates to cigar cutters, more particularly of the class which consists of a guide plate and a cutter plate, adapted to slide one upon the other, the cutter plate being provided with a sharpened cutting end and the guide plate with a coöperating sharp edged opening through which the cigar is positioned to have its end cut off by the moving of one plate upon the other, the guide plate having its edges rolled up forming ways in which the cutter plate slides, and both plates being provided with longitudinal registering grooves formed in their inner or contacting surfaces forming tubes in each of which is located a coil spring each connected at its opposite ends to said opposite plates whereby the plates are adapted to be manually actuated to sever the cigar tip and returned to normal or open position by the action of said springs. By this construction the two plates may be completely formed by machinery rendering the production of a cutter so formed most practical and inexpensive.

With these and other objects in view, the invention consists of certain novel features of construction, as will be more fully described and particularly pointed out in the appended claims.

Of the accompanying drawings: Figure 1— is a front elevation of my improved cutter showing the same in extended or normal position. Fig. 2— is a detail in perspective showing the inner face of the guide plate. Fig. 3— is a perspective view of the cutter plate showing the outer face thereof. Fig. 4— is a section on line 4—4 of Fig. 2. Fig. 5— is a section on line 5—5 of Fig. 3. Fig. 6— is an enlarged section on line 6—6 of Fig. 1. Fig. 7— is a detail of one of the coil springs showing the eyes in the ends for engaging the pins in the opposite plates.

Referring to the drawings, 10 designates the cutter plate, one end of which is provided with a V-shaped notch as at 11, the end of which is sharpened to form one of the cutters. The opposite end of this plate

is provided with an opening 12 through which the thumb or finger of the operating hand may pass. This cutter plate is also provided with two longitudinal grooves 13 and 14, set inward a short distance from its corresponding edges 15 and 16, said grooves being formed by pressing the stock from the inner side of the plate outward. Attaching pins or lugs 17 extend inward from the wall of each groove, the same being located near the cutter end of the plate.

18 designates the guide plate whose side edges are turned up and over toward each other forming grooves or ways 19 and 20 into which the edges 15 and 16 of the guide plate are adapted to slide and which ways also serve to hold the faces of the opposite plates in sliding contact with each other. The center of this guide plate is provided with an opening 21 whose edge is beveled from the outer side inward providing a co-operating cutting opening through which the end of the cigar is passed to be cut off when the plates slide inward one upon the other. The inner surface of this guide plate is also provided with a pair of longitudinal grooves 22 and 23 pressed from the inner face thereof outward, the same being arranged to register with those of the cutter plate thereby forming between them two halves of two tubular portions in which the actuating coil springs 25 are located. The grooves 22 and 23 in the guide plate are also provided with inwardly extending pins or lugs 24 which are located at the end of the grooves opposite to that of the location of the pins 17 in the cutter plate. These pins or attaching members in both the guide plate and the cutter plate may be inserted or formed in any suitable manner, but I have shown the same as being a portion of the stock of the tube cut out and bent inward forming retaining hooks, pins or lugs to which the opposite ends 26 and 27 respectively of the springs 25 may be attached.

In assembling the parts of my improved cutter the springs 25 are placed in the grooves 22 and 23 in the guide plate, the loops at the ends 26 engaging the pins 24. The cutter plate is now placed in position with its edges in the ways of the guide plate and is slid inward until the stock 17 which has been cut but not yet been turned inward to form the pins, comes opposite the eyes in the ends 27 of the spring, these lugs are 110

then bent inward engaging the eye at the end 27 of the spring. Thus the two members are permanently connected together, the springs 25 upon being compressed between the pins 17 and 24 determine the extent of the opening motion of the plates, and the pins 17 in the cutter plate upon bringing up against the lower end walls of the grooves 22 and 23 on the guide plate limit the motion in the opposite direction.

I have shown and described the guide plate 18 as being provided with its edges turned over those of the cutter plate, but I do not wish to be restricted to this particular construction as the edges of the cutter plate may be turned over those of the guide plate the device working equally well in either case.

In operating my improved cutter it is only necessary to press with the thumb and finger on the outer ends of the two opposite plates causing the V-shaped cutting edge of the cutter plate to slide across the opening in the opposite plate thus cutting the top of the cigar which may be inserted through said opening. When the pressure is released the two plates return at once to normal or extending position under action of the springs 25.

By locating the groove halves in the inner faces of the opposite members of the cutter a tubular portion is formed in the simplest and most practical manner for housing the springs, thereby providing a cutter of the most inexpensive and yet practical construction.

I claim:

1. A cigar cutter comprising two opposite contacting plates each provided with opposing cutting portions and adapted to slide one upon the other, the inner or contacting faces of said plates being provided with registering grooves which between them form a tubular portion providing a housing for

the actuating spring, a spring in said housing having its opposite ends attached respectively to said opposite plates whereby said plates after being actuated to cut the cigar end returns to normal under action of said spring.

2. A cigar cutter comprising two opposite contacting plates each provided with opposing cutting portions the edges of one being rolled over those of the other to guide one to slide upon the other, the inner or contacting faces of said plates being provided with registering grooves which between them form a tubular portion providing a housing for the actuating spring, a spring in said housing having its opposite ends attached respectively to said opposite plates whereby said plates after being actuated to cut the cigar end returns to normal under action of said spring.

3. A cigar cutter comprising a cutter plate sharpened at one end, a guide plate with an opening through it having a co-acting cutting edge, said latter plate having its opposite edges rolled over forming ways in which the corresponding edges of the cutter plate slide the inner or contacting faces of both plates being each provided with two parallel longitudinal oppositely disposed grooves which together form two halves of a tube, an inwardly turned pin at the opposite ends of each opposite pair of grooves, a coil spring in each tube, each spring having its opposite ends attached to the pins in said opposite plates whereby said plates may be manually slid one upon the other to cut the cigar and returned to normal or open position by the action of said springs.

In testimony whereof I affix my signature in presence of two witnesses.

CHARLES H. PATTEN.
